COMBINED TOOTHPICK DISPENSER AND HOLDER FOR CONDIMENTS DISPENSERS

Benjamin A. Hunt, Box 2803, Dallas, Tex.

Filed Feb. 17, 1964, Ser. No. 78,659

Term of patent 14 years

(Cl. D52—2)

Fig. 1

Fig. 2

Fig. 3

The rear of the article is substantially the same in appearance as the front shown in FIGURE 3.

I claim:

The ornamental design for a combined toothpick dispenser and holder for condiment dispensers, substantially as shown and described.
